UNITED STATES PATENT OFFICE.

PAUL R. HAHNEMANN, OF MOUNT VERNON, NEW YORK, ASSIGNOR TO MAX AMS MACHINE CO., OF MOUNT VERNON, NEW YORK, A CORPORATION OF NEW YORK.

POWER-PRESS.

972,369.

Specification of Letters Patent. Patented Oct. 11, 1910.

Application filed January 5, 1910. Serial No. 536,507.

To all whom it may concern:

Be it known that I, PAUL R. HAHNEMANN, a subject of the Emperor of Germany, residing at Mount Vernon, New York, in the county of Westchester and State of New York, have invented certain new and useful Improvements in Power-Presses, of which the following is a specification, reference being had therein to the accompanying drawing.

My invention relates to improvements in power presses, more particularly of the toggle draw press type and has special reference to an improved means for holding the work in position while being operated upon.

In the accompanying drawings I have illustrated in Figure 1 a vertical elevation of a press embodying an application of my invention. Fig. 2 is a cross section on the line 2—2 of Fig. 1 looking from left to right. Fig. 3 is a plan view of a slide member, and Fig. 4 a section on the line 4—4 of Fig. 3. Fig. 5 is a diagrammatic illustration of the position of the connecting links or rods when the holding means are elevated, and Fig. 6 is another diagrammatic illustration of the same when the holding means have descended upon the blank while the same is being drawn.

7 is the usual crank shaft of a draw press provided with the pitman 8 connected to the plunger or inner slide 20 in which may be mounted the usual draw punch such as 21.

Upon the side of the frame 9 of the press is provided guide-ways 10 and 11 in which may be mounted the slide member 12 shown more particularly in Figs. 3 and 4. The crank shaft 7 is also provided with a crank or eccentric 13 upon which is mounted the lever 22, the other end of said lever being mounted within the slide member 12 as shown, so that when the pitman is nearly at the limit of its stroke, the slide is at the limit of its downward stroke.

14 and 15 are rocker shafts suitably mounted upon the framework of the press as shown and provided with cranks upon which are mounted the connecting links such as 16 and 17. From the rocker shaft 14 a crank 18 projects into the groove 19 of the slide member 12 and the same is true of the shaft 15, the general arrangement being seen to advantage in Fig. 2. The result is that as the slide member 12 is elevated by the rotation of the crank or eccentric 13, the

crank 18 of the rocker shaft 14 and a similar crank on the rocker shaft 15, are caused to slide within the curved slots of the slide member thereby separating in following said slots. This separation of the cranks of the rocker shafts 14 and 15 causes said shafts to rotate and depress the connecting links attached to the cross heads 27 and 28 adjustably secured to the outer slides 23 and 24 which firmly holds the blank in position while the draw punch mounted in the plunger operated by the pitman descends and operates upon the work. Upon continuing the rotation of the main shaft 7, the slide member descends allowing the cranks engaging the slots thereof to slide upwardly within the same, again assuming the position shown in Fig. 5 in which position the work is released and may be shifted. The connecting links 16 and 17 may of course be adjustably connected to the outer slides 23 and 24 as by the screws 25 and 26.

29 is the bed of the machine in which the die is set and over which the blank is fed.

From this arrangement it will be seen that an intermittent motion is provided for the outer slide or holder for the blank and all the advantages of the toggle press are obtained without the use of the toggle links usually employed, the blank being held securely and not wrinkling during the descent of the punch.

Various modifications may be made without departing from the spirit of the invention as set forth in the claims.

Having described my invention, what I claim as new, and desire to secure by Letters Patent, is:

1. In a draw press, the combination with the framework of the main crank shaft carrying a pitman and punch, and a rocker shaft carrying connecting links and a blank holder, a slide member provided with curved slots, cranks upon said rocker shaft engaging said slots and other cranks thereupon being adapted to operate said blank holder, and means in combination therewith whereby said blank holder binds the blank in advance of operation upon said blank by said punch.

2. In a draw press, the combination with the framework of the main crank shaft carrying a pitman and punch, and rocker shafts carrying respectively connecting links, cross heads and a blank holder, a slide member

provided with guide ways, means in combination with said rocker shafts for engaging said guide ways and other means in combination therewith for operating said blank holder, and means for binding the blank by said blank holder in advance of operating upon said blank by said punch.

3. In a draw press, the combination with the framework of the main crank shaft carrying a pitman and punch, and rocker shafts carrying respectively connecting links, cross heads and a blank holder, a slide member provided with curved slots, cranks upon said

rocker shafts engaging said slots, other cranks thereupon for operating the blank holder, means in combination with said main crank shaft for reciprocating said slide member, and means for securing said blank by said blank holder before said punch operates upon the same.

In testimony whereof I affix my signature in presence of two witnesses.

PAUL R. HAHNEMANN.
